UNITED STATES PATENT OFFICE.

CLARENCE N. SCOTT, OF HOUSTON, TEXAS, ASSIGNOR TO INTERNATIONAL STEAM PUMP COMPANY, A CORPORATION OF NEW JERSEY.

FLAP-VALVE.

1,022,157.

Specification of Letters Patent.

Patented Apr. 2, 1912.

Application filed August 4, 1911. Serial No. 642,327.

To all whom it may concern:

Be it known that I, CLARENCE N. SCOTT, a subject of the King of Great Britain, residing at Houston, county of Harris, and 5 State of Texas, have invented certain new and useful Improvements in Flap-Valves, fully described and represented in the following specification and the accompanying drawings, forming a part of the same.

10 This invention relates to an improved flap valve intended especially for use in large compressors or blowing engines, but generally applicable for flap valve uses and with either liquids or gases.

15 In the present blowing engine practice, flap valves formed of elastic plates are commonly used, which are opened by the air pressure and of sufficient elasticity to seat after the discharge stroke. A serious diffi-

20 culty in such valves results from the fact that it is commercially impracticable to secure perfectly flat plates, the rolling of the plates resulting in curvature in both directions so that the plates may best be de-

25 scribed as buckled. The result is that the valves will not lie flat against the seats, and when forced against the seats by pressure an abnormal stress is set up in the valve plate, which applied frequently soon results

30 in plate fracture. Moreover, the valves with flat valve seats are not under sufficient tension to seat before the piston reverses, so that they are then seated with considerable force by the air pressure which racks the

35 valves and is liable to cause the corners of the valve plates to break off. The valve plates with flat valve seats, moreover, are subject to reversal of stress, the outer fibers being alternately under and relieved from

40 tension or compression, resulting in weakening and shortening the life of the buckled valve plates. I avoid these difficulties, and greatly lengthen the life of the valve plates, by using a curved seat and backing the valve

45 plates with one or more spring plates pressing upon the valve, several of these spring plates preferably being used and decreasing in width, so that the pressure of the spring plates decreases toward the free edge of the

50 valve, and these spring plates are preferably cut away to form fingers extending toward the free edge of the valve. With the curved seat, the initial spring tension on the valve plates is increased, thus securing the seating

55 of the valve when the piston has completed

its discharge stroke, and prevents air pressure from seating the valves with consequent liability to breakage. The spring plate backing aids, also, in seating the valves and tends to reduce the buckle in the valve 60 plates. The ill effects of stresses in buckled plates are minimized or overcome, largely because there is no reversal of stress in the valve plates, the outer fibers of the plate toward the seat being always in tension, and 65 the outer fibers toward the guard being always in compression, whether the valve is open or closed, so that the only effect of opening the valve is to increase these stresses.

70 In the accompanying drawings forming part of this specification, the invention is illustrated as applied in a valve construction of common blowing engine type, and this construction will now be described in detail, 75 and the features forming the invention then specifically pointed out in the claims.

In the drawings, Figure 1 is a cross section through the valves, valve seats and guards. Fig. 2 is a longitudinal section on 80 the line 2 of Fig. 1. Fig. 3 is a horizontal section on the line 3 of Fig. 1.

Referring to the drawings, A is the valve head having passages 10 and valve seats 11, the latter being divided into comparatively 85 narrow ports *a* forming a multiported seat, and B the curved guards or abutments against which the valves open, these guards being carried by supports C. The valves *b* are formed of spring plates of such length 90 as to extend over and close the series of ports *a*. These are shown as formed of a single plate, but, with the usual pressures, may be and preferably will be formed of a number of thin plates to secure the desired 95 elasticity. The construction thus far described is of well-known type, but may be of any other suitable construction.

Referring now to the features of the present invention, the valve seat 11, instead 100 of being flat, as usual, so that the valve is not under tension when closed, is curved widthwise of the valve so that the valve is bent outward or toward the guard, and under tension when closed, and the valve 105 plates *b* are backed by spring plates under tension to press upon and close the valve, four of these plates being shown, *c'*, *c''*, *c'''*, *c''''*. These plates *c'*, *c''*, *c'''*, *c''''*, are preferably of different widths as shown, so 110

that the desired elasticity of the combined valve plates and backing plates is secured, and these backing plates are preferably cut away to form a series of spring fingers acting on the valve plates. The valve plates and backing plates are shown as secured together between the guards and valve supports 13 by pins passing through openings in the base of the plates, as usual 10 with valve plates in constructions of this type, but it will be understood that they may be mounted in any other suitable manner.

It will be understood that the curved seats with plate valves under tension when closed may be used without the spring backing plates, and such use is within the invention, but the spring backing plates secure important results in avoiding the ill effects of buckled valve plates, and undue 20 wear and liability to breakage of the valves when seating, and the combination of the two features is important in enabling large valve plates to be used without the ill effects of buckling, and in lengthening the life 25 of such valve plates.

What I claim is:

1. In a flap valve, a valve seat slotted to form a plurality of ports and curved to maintain the valve under tension when closed, 30 in combination with an elastic plate extending over the series of ports and unslotted so as to form a continuous plate valve controlling the series of ports.

2. In a flap valve, a valve seat slotted to 35 form a plurality of ports and curved to maintain the valve under tension when closed, in combination with an elastic plate extending over the series of ports and unslotted so as to form a continuous plate valve 40 controlling the series of ports, and a spring plate backing pressing the valve toward its seat.

3. In a flap valve, a valve seat slotted to 45 maintain the valve under tension when closed, in combination with an elastic plate extending over the series of ports and unslotted so as to form a continuous plate valve controlling the series of ports, and a

spring plate backing formed of a series of 50 spring plates of widths decreasing from the free edge of the valve plate and pressing the valve toward its seat.

4. In a flap valve, a valve seat slotted to 55 form a plurality of ports and curved to maintain the valve under tension when closed, in combination with an elastic plate extending over the series of ports and unslotted so as to form a continuous plate valve controlling the series of ports, and a 60 spring plate backing formed of a series of spring fingers of widths decreasing from the free edge of the plate and pressing the valve toward its seat.

5. In a flap valve, the combination with 65 a valve seat curved to maintain the valve under tension when closed, of an unslotted elastic plate valve, and a spring plate backing pressing the valve toward its seat.

6. In a flap valve, the combination with 70 a valve seat curved to maintain the valve under tension when closed, of an unslotted elastic plate valve, and a spring plate backing 75 pressing the valve toward its seat, and consisting of series of spring plate fingers.

7. In a flap valve, the combination with 80 a valve seat, slotted to form a series of ports, of an elastic plate extending over the series of ports and unslotted so as to form a continuous plate valve controlling the series of ports, and a spring plate backing formed of a series of 85 spring plates pressing the valve toward its seat.

8. In a flap valve, the combination with 90 a valve seat, slotted to form a series of ports, of an elastic plate extending over the series of ports and unslotted so as to form a continuous plate valve controlling the series of ports, and a spring plate backing consisting of a series of 95 spring fingers pressing the valve toward its seat.

In testimony whereof, I have hereunto set my hand, in the presence of two subscribing witnesses.

CLARENCE N. SCOTT.
